UNITED STATES PATENT OFFICE

ELMER LOVELL SMITH, OF SPRINGFIELD, MASSACHUSETTS, ASSIGNOR TO PACKAGE MACHINERY COMPANY, OF SPRINGFIELD, MASSACHUSETTS, A CORPORATION OF MASSACHUSETTS

WRAPPING MACHINE

Application filed March 17, 1926. Serial No. 95,436.

This invention relates to improvements in wrapping machines.

The novel features to be hereinafter described are applicable to all machines of this general character, but for illustrative purposes a machine for wrapping rectangularly shaped articles will be described.

One object of the invention is to provide means for guiding the wrapping material across the open mouth of a wrapping wheel while the wrapper is being delivered thereto and is accomplished by actuating the guiding means towards and away from the delivering means.

Another object of the invention is the provision of means movable in a pocket of the wrapping and other means for pressing an article and wrapper thereagainst, which acts in conjunction with the pressing means to clamp the article and wrapper therebetween as they are advanced into the pocket so that the wrapper is held from shifting with respect to the article.

Another object is the provision of means operable by the article-advancing plunger for ejecting an article from the wrapping wheel whether or not an article is inserted thereinto by said plunger.

Another object of the invention is the provision of adhesive applying means, the operation of which is controlled by the condition of plasticity of the adhesive material.

Other objects and advantages will appear from the following description of the invention which is illustrated in the form at present preferred by means of the accompanying drawings, in which:

Fig. 1 is a plan view of a machine embodying the features of my invention;

Fig. 2 is a sectional elevational view on the line 2—2 of Fig. 1;

Fig. 2b is a diagrammatic view representing the path of the article transporter;

Fig. 3 is an enlarged side elevational view of a portion of the machine taken on the line 3—3 of Fig. 1 and shows the adhesive applying mechanism and operating means therefor;

Fig. 3a is an isometric view of the member movable in the pocket of the wrapping

wheel and the end tuckers of said wheel;

Fig. 4 is a sectional elevational view taken on the line 4—4 of Fig. 1 showing the tumble box operating mechanism;

Fig. 5 is a diagrammatic isometric view showing the plungers for operating on the article;

Fig. 6 is an isometric view of the reciprocating guide for the wrapper sheets; and

Figs. 7 to 12, inclusive, are isometric views showing the manner of folding the wrapper about the article.

Referring now to the drawings in detail, a bed 1 and side supporting frames 2 and 3 are suitably secured together and arranged to support the mechanism constituting the invention. A drive shaft D rotatable in suitable bearings of the frames 2 and 3 may be driven from any suitable source of power, such as a line shaft belted therefrom to a pulley fixed on either end of said shaft but which has been omitted in the drawings for clearness.

The articles A may be fed to the machine by a feed belt B of ordinary construction so as to be delivered thereby in the direction of the arrow a in Fig. 1 and onto a support or chute 4 which is provided with oppositely disposed side guideways 5 for guiding the articles into proper position with respect to the mechanism for advancing the same through the machine.

I preferably employ a belt feed of the intermittently operating type arranged so that a line of articles in the chute is urged against a stop plate 6 at the end of the chute. The stop plate is preferably positioned so that it will locate the article bearing thereagainst accurately beneath and in alignment with a vertically reciprocating plunger 8, and the chute 4 is disposed so as to convey the articles at a level above that of a plunger 9 which advances it into the wrapping mechanism. The article, as it abuts the plate 6, is unsupported by the chute by reason of the chute at this point being cut away to allow the article to be forced downwardly therethrough onto a table 10.

The articles, arranged in line in end to end relation in the chute or one abutting the

next and being urged forwardly by the belt, will exert a sufficient pressure upon the endmost article abutting the plate to hold it from falling of its weight into the path of plunger 9. The supporting table 10 is fixed to the bed and has its supporting face arranged to receive the endmost article and support it in alignment with a pocket 11 of a wrapping wheel or tumble box 12.

10 The plunger 8, referred to, is secured to a bracket 13 pivotally carried on the ends of levers 14 and 15, which are oscillatable on shafts 16 and 18 fixed in spaced-apart bearings 17 fixed to bed 1. A rearwardly 15 extending arm 19 of the lever 18 is pivotally connected to the end of a connecting rod 20 which is fixed to a yoke 21 slideable on the driving shaft D. A cam of suitable form fixed on said shaft operates on a cam roll 20 22 of the yoke 21 and is arranged to actuate the plunger 8 up and down in a proper timed relation with respect to the other parts of the machine, the arrangement of the levers 14 and 15 being such that the 25 plunger will be maintained in a level position during its up and down movement.

The plunger 9, having a forwardly depending portion 25, is fixed to a member 26 which is slideable back and forth on a guide 30 rod 27 supported by the table 10 and a bracket 28. A downwardly extending portion 29 of the member is arranged to straddle a bar 30 fixed to the underside of the bed and is adapted to maintain the member 35 and plunger 9 in a level position during the reciprocation thereof.

The plunger member 26 is connected by a link 31 to the upper end of a lever 32 mounted to swing on a rock shaft 33 extending 40 between the supports 2 and 3 and receiving its motion from an eccentric 34 fixed on the driving shaft D and connected thereto by a connecting rod 35.

45 Portions 36, extending from opposite sides of the member 26, have in screw threaded engagement therewith, so as to be adjustable, forwardly extending ejectors in the form of rods 39 which, as will later appear, are arranged to actuate a movable 50 member of the wrapping wheel. These ejectors are carried forwardly with the plunger 9 in each forward movement thereof. The mechanism just described is preferably arranged so that the plunger 9 will 55 operate after an article has been deposited on the table 10 to advance it and a wrapper sheet into a pocket of the wrapping wheel.

60 The wrapping material, which may be in the form of sheets, is delivered to the machine by any suitable feeding mechanism such as is disclosed in my pending application Patent No. 1,656,084 Jan. 10, 1928, and may be received between vertically disposed guides 40 supported above the machine 65 which are arranged to direct the sheet of

wrapping material between the table 10 for supporting the article and a pocket 11 of the wrapping wheel.

Ordinarily, a movable guide for guiding the paper is disposed in the path of the article to be advanced into the wrapping mechanism and is arranged to be moved out of the path by the advancing article or plunger so as to allow the article to be inserted into the wheel. According to one novel feature of my invention, I eliminate the necessary mechanism therefor and provide guiding means movable in and out of the path of the article which receives and guides the sheet and is so arranged as to be positively moved out of the path of the advancing article at a certain time, and consists of the following. Guide members 42 having slots 43 in the upper ends thereof to form separated side guide bars 44 for receiving therebetween the lower end of the wrapping sheets are mounted in a spaced relation on a vertically movable member 45, supported on the ends of levers 46 and 47 which are oscillatable on pivots 48 of a bracket 49 fixed to the under side of the bed 1. The lever 47 has a depending arm 50 which is connected to an eccentric 51 fixed on the shaft D and by the means of which the levers are oscillated to move the guides up and down between the position shown and that represented by dotted lines as in Fig. 6.

The double lever arrangement described is desirable as the levers will operate in parallelism and thereby will maintain the guides in a substantially vertical position at all times. While the plunger 9 is in the position shown, the guides may be timed so as to be in their upper position so that the sheet S is delivered thereinto by the guides 40. As the sheet continues to descend between the guides, they are lowered simultaneously therewith so as to be out of the path of the article as it is being advanced forwardly by the plunger 9.

In order to properly position the sheets so that it will register with the articles in the desired manner, sheet supporting or stop members 52 are provided against which the lower end of the sheet may rest. These comprise upwardly and forwardly extending arms fixed to a shaft 53 that is oscillatable in the bed 1. A slotted lever arm 54, fixed to the shaft adjacent the outer side of the bed, may be secured in various positions of adjustment by means of a screw 55 whereby the stops 52 may be adjusted to support the wrapper sheets in various positions.

The wrapper sheet S will, by means of the mechanism just described, be positioned so that, as the article is advanced thereto as in Fig. 7, the said article and wrapper may be inserted in a pocket of the wrapping wheel now to be described.

The wrapping wheel 12 comprises upper 130-

and lower walls 60 that may be integral with forks 61 at opposite ends thereof. Shafts 62, secured to the forks and to the walls, are rotatable in bearings 63 carried by the bed 1 so that the wrapping wheel and forks may be rotated as a unit in the direction of the arrow or clockwise to transfer an article and wrapper to a wrapping chute or chaminel.

Plates 64 are resiliently mounted in the well known manner adjacent the inner faces of the members 60 and are adapted to yieldingly embrace the wrapper and opposite sides of the article for folding the wrapper about three sides of the article as shown in Fig. 8, as they are inserted therebetween by the plunger 9.

Side folders 66, arranged in pairs so as to engage opposite ends of the article, are carried by the upper and lower plates 60 and are preferably adjustably secured thereto by means of screws 67. These folders 66 are arranged and adapted to embrace the ends of the article and to tuck the wrapper, as at b in Fig. 8, as the wrapper and article are inserted therebetween and into the pocket of the wheel. It will be noted by reference to Fig. 8 that an extension of flap c of the wrapper will project outwardly from the pocket of the wheel in the well known manner.

These folders 66 are, as usual, spaced at top and bottom from the face of the plates 60 so as to permit the extensions c and c' of the wrapper to extend between them and the plates, as is customary in devices of this character, and are spaced apart as shown to form a slot 67' therebetween for the purpose now to be described. A bar 68, disposed in parallelism with the axis of rotation of the wrapping wheel, has reduced portion 68' for movement in the slot 67' between the folders 66 and at its opposite ends is fixed to rods 69 slidable in the yokes 61. Plates 70, fixed to the bar 68 between the end folders, are arranged so as to form, in conjunction with the bar, a block or movable bottom for the pocket. It will be noted that the plates 70 are spaced apart to form an opening therebetween through which a transporter pusher member may operate, engaging the rear side of an article after it has been ejected therefrom. When the wheel is positioned for receiving an article and wrapper, the bar is located in the opposite end of the pocket from that shown in Fig. 2 and in which position the forward plates 70 have their forward face substantially flush with the edges of the tension plates 64 at the receiving side of the pocket. As the article and wrapper are brought into engagement therewith by the plunger 9, the article and wrapper will be clamped between the plate and plunger so that the wrapper will not shift relative to the article and the plunger, in advancing, will move the plate and bar rearwardly of the pocket as the article is inserted thereinto and at the same time will eject an

article from the other side of the pocket into a folding chute.

With the bar 68 in the receiving position just described, the rods 69 will extend towards the ejectors 39 and will, if there is no article in the pocket, be engaged by the ejectors 39 as the plunger 9 advances in a feeding movement whereby the ejectors will move the bar rearwardly of the pocket and thereby eject an article and wrapper from the pocket of the wrapping wheel. The ejectors 39, however, are preferably so adjusted that there will not be a contact of the ejectors 39 and rods 69 whenever there is an article in position on the table 10 to be inserted into the pocket by the plunger 9, in which case the article will act to move the so-called tumble box bottom for ejecting the article at the opposite side of the pocket.

The wrapping wheel receives its intermittent rotary motion by means of the mechanism shown in Fig. 4 wherein a pinion 72 fixed to and driven by the shaft D is in meshing engagement with a gear 73 rotatable on a stud 74. Rolls 75 on the face of gear 73 enter slots g of a geneva G in the well known manner to rotate said geneva, which is rotatable on a stud 76, and a gear 77, integral with said geneva, is in meshing engagement with a driven pinion of the shaft 62 of the wrapping wheel. Keepers 73' of well known form are carried by the gear 73 and are, as usual, arranged to prevent a rotation of the geneva as the driving rolls are rotated from engagement with one slot and into another.

As the article is rotated by the wheel in a clockwise direction, the extending wrapper flap c is frictionally engaged by a wiper W pivoted to a support W' and which is urged against the article and wrapping wheel by a spring w of usual form. As the wrapping wheel comes to rest, the article and wrapper are in the form shown in Fig. 9 and may then be ejected into the folding chute.

As the article and wrapper are ejected from the pocket of the wheel either by the insertion of an article at the other side thereof or by the action of the ejectors, all of which has been previously explained, it is advanced into the mouth of a folding chute which chute, aside from its novel characteristics as will be more particularly pointed out, is of well known form and comprises the following. Bars 78 are provided that extend longitudinally of the machine and are adjustably secured by screws 78' to a vertically adjustable transverse member 79. The member 79 is slidable on guides such as rods 80 that are fixed to the bed and have teeth 81 cut in their forward faces. A shaft 79', mounted for rotation in the member 79, has fixed thereto gears 82 which intermesh with the teeth 81 of the rods and as the said shaft is rotated, the member will be raised or lowered to various positions of adjustment. The member

W', previously referred to, is adjustably supported by the bars and plates 83 and 83' yieldingly supported by the bars from the top of the chute and acts to yieldingly press the article and wrapper against the bottom of the chute and to lay the extending portion *c* of the wrapper against the article as in Fig. 9 as the article and wrapper are advanced thereunder.

10. The lower side of the chute for supporting the article is formed of bases or tables 85 that extend in the direction of travel of the article and are adjustably secured to the upper side of the bed by screws 86. These members are 15 spaced apart so as to allow a transporting mechanism to operate therebetween on the articles and are made adjustable so that they may be moved towards or away from one another to accommodate articles of different 20 sizes.

End tuckers 88 are secured to the members 85 and function in the ordinary manner to form the tuck *d* in the wrappers as the article and wrapper are advanced into the chute. 25 The article and wrapper are preferably advanced in a step-by-step manner through the chute by a transporter mechanism later to be described, and during the movements of the article the various folding operations are 30 performed by means of the following.

Folders 90, carried by the bars 78, are formed so as to lay the flap *e* against the ends of the article as it is moved to the position represented by dotted lines P' in Fig. 2. As the 35 article is advanced and left in this position, the lower wrapper extensions *f* which project outwardly from the ends of the article receive a daub of adhesive material as represented thereon by *X* from a daubing mechanism 40 which will presently be described.

The transporting mechanism referred to will now be described with particular reference to Figs. 1, 2, and 3.

A central web 100 has downwardly depending lugs 101 and carries on its upper side a plurality of article engaging or pusher members 102. The forward pusher member 102 is adapted in the operation of the transporter to enter between the plates 70 in 50 order to engage the rear face of an article ejected from the pocket of the wheel. A bracket 103 fixed to the under side of the bed has swinging levers 104 pivoted thereto that have their lower ends connected to links 105.

55 Said links 105 are pivotally connected intermediate their ends to the lugs 101 of the web member 100, and their other ends are pivotally carried on the ends of rotatable cranks 106, fixed to the inner ends of short shafts or studs 60 107 rotatable in the support 2. As the shafts 107 are rotated, the member 85 will be given a raising and lowering movement as well as a movement back and forth within the chute and the parts are preferably so designed that 65 the pushers are carried in a path as diagram-

matically represented in Fig. 2b. That is to say, each of the pushers will engage the rear face of the articles in the chute and advance them simultaneously therealong the desired or required distance during each cycle of operation of the machine. As the transporter reaches the forward end of its stroke, as will be seen in the diagram, the pushers return for another article advancing movement by a lowering and a rearwardly directed motion. 70

75 The shafts 107 receive their rotary motion by means of the mechanism shown in Fig. 3. A driving pinion 108 fixed on the shaft D is in driving engagement with a gear 109 fixed on shaft 107 at the left for driving said shaft, while a connecting rod 110, pivotally connected to said gear 109 and to the end of a crank 111 fixed on the other of the shafts 107, imparts a rotary motion to the latter. The web member 100, together with the links 101 connecting it to links 105, operates as a second connecting rod to prevent stalling of the right hand shaft 107 as the driven shaft 107 passes dead center.

80 One of the adhesive applying mechanisms referred to will now be described and is adapted and arranged for use in connection with the ordinary adhesive materials, although it is particularly designed for use in connection with molten sealing wax or the like. A reservoir or box 115 adjustable along a swinging arm 116 has a rotatable shaft 117 to which is fixed a daubing roll or wheel 118 located within the box and a ratchet wheel 119 outside of said box. A lever 120, pivoted on said shaft 117, has its end pivotally connected to a link 121 which has its lower end connected to a member 122 fixed to the bed 1. A pawl 123, carried by the lever 120, is arranged to engage with the teeth of the ratchet 119 and as the 85 box is raised by the lever 116, since the end of lever 120 will be held from a raising movement, the pawl 123 will ride over the teeth of the ratchet. As the lever and box descend, the pawl in engagement with the ratchet will 90 cause a rotation thereof and will bring the face of the roll 118 carrying the adhesive from within the box so that it will be applied to the extending wrapper flap *f*. A scraper 124, adjustable on the box and arranged to be 95 positioned adjacent the periphery of the wheel 118, is adapted to regulate or control the thickness of the film of adhesive in the well known manner.

100 A heating element E, which may be in the form of an electrical resistance unit, is provided for insertion in a side of the box and may easily be controlled for maintaining the plasticity of the material in any desired degree.

105 When the sealing wax is hardened by cooling, it will be obvious that it would be difficult to rotate the wheel 118 without liability of injuring the mechanism and in order that the lever and box may not be forced downwardly 110

by the operating mechanism, I provide the following.

The levers 116 are rotatable on an oscillatable shaft 130 and have upwardly extending arm portions 131 which carry adjusting screws 132. A central lever 133 fixed to the shaft 130 between the levers 116 has a transverse bar 134 secured thereto at its upper end that extends across the path of said screws 132. As the lever 133 is moved to the right, the bar will engage the studs 132 and move the levers 131 to the right to elevate the boxes 115. As the lever 133 moves to the left, the levers 131 will follow such movement or not, according to whether the adhesive material is sufficiently plastic to allow a rotation of the wheel 118. If the material permits a rotation of the wheel, the box and lever will move downwardly so that the wheel will apply a daub of adhesive to the extending wrapper flaps as at X.

The shaft 130 is oscillated by means of the following. A downwardly depending lever 135, fixed to said shaft 130, is pivotally connected to a link 136 which is similarly connected to a member 137 fixed to a stud 111' of the crank 111.

As the crank 111 is rotated by the connecting rod 110 for actuating the transporter, the inner end of the member 137 is rotated about the axis of the shaft 107, whereby the arm 135 is moved back and forth to raise the lever 116 and to allow it to subsequently descend for an adhesive applying operation.

In the operation of the machine, articles to be wrapped and sheets of wrapping material are delivered to the feed channel 4 and guides 40 respectively. As has been explained, the articles in the channel are in end to end contact and the action of the feed belt will force the endmost article against the stop plate 6, and the plunger 8 in the lowering movement will carry the endmost article downwardly onto the table 10. During this downward movement of the plunger 8, the wrapper sheet guides 42, which have been elevated to receive the lower end of the sheet, are moved downwardly simultaneously with the sheet, the lower edge of which comes to rest upon the positioning stops 52. The guides 42, however, continue downwardly to their lowermost position wherein they are below and out of the path of movement of the plunger 9. The wrapping wheel pocket 55 is positioned to receive an article and wrapper in which position the bar 68 and plate structure are at the receiving end of the pocket.

The plunger 9 on advancing engages the side of an article on the table 10 and moves it into engagement with the vertically disposed wrapper sheet and by its continued advancing movement clamps the sheet between the article and a movable plate 70 or bottom of the wrapping pocket. The bar 70 and

plates 64 of the wheel will preferably offer some resistance to the advancing movement of the plunger and are desirable in order to firmly clamp the wrapper between the article and plate so as to hold the wrapper from a shifting movement with respect to the article. The movement of the plunger will force the article and wrapper into the pocket and cause the bar and plate to eject an article from the opposite side of said pocket into the folding chute.

If for any reason an article is not positioned for the action of the plunger 9, the ejectors carried thereby will, on being advanced, engage the rods 69 fixed to the bar of the wrapping wheel and will move the same to effect an ejection of an article if carried by the pocket at its discharging side.

As the article and wrapper are inserted in the wheel, the wrapper will extend from the upper side thereof as at C; and as the wheel is rotated in a clockwise direction, the flap will be engaged between the wiper W and wrapping wheel and pulled tightly about the article and will assume the position shown in Fig. 9.

As the article and wrapper are ejected into the folding chute, the flap extension is laid against the upper side of the article by the plate 83, while the tucks d are made in the end extensions of the wrapper by the folding blades 88.

The article is advanced by the transporter in a step by step manner throughout the length of the folding chute and, during these movements, the end extensions e are folded against the ends of the articles while, when at rest in the position P', adhesive material is daubed on the extensions f by the daubing mechanism. The next subsequent movement of the transporter advances the article by the folder 140 which presses the extension f upwardly against the ends of the article.

The completely wrapped articles are advanced to the supports at the end of the machine from which they may be removed by the operator.

While the invention has been described in the form at present preferred, I am aware that many changes may be made in the form thereof without departing from the scope thereof and I therefore prefer to be limited by the appended claims rather than by the description.

What I claim is:

1. A wrapping machine comprising in combination, a wrapping wheel having opposed openings for receiving articles to be wrapped, means actuated by an article delivered into one opening for ejecting an article from the opposed opening, and means operable only in the absence of an article to be delivered into one opening for expelling an article from the opposed opening.

2. A wrapping machine comprising in com-

bination, a wrapping wheel having a pocket extending therethrough for receiving an article, a member movable in the pocket by an article inserted at one side thereof to eject an article at the other side thereof, means for delivering an article into the pocket, and connections between the delivery means and the member operable only in the absence of an article to be delivered into the pocket for shifting the plunger to eject an article from the pocket.

5 3. A wrapping machine comprising in combination, a wrapping wheel having a pocket extending therethrough for receiving an article, a member movable in the pocket by an article inserted at one side thereof to eject an article at the other side thereof, a plunger for delivering an article into the pocket at one side of the wheel, and projections carried 10 by the plunger of insufficient length to reach said member in the presence of an article but operable to shift the member to eject an article from the wheel in the absence of an article being delivered into the wheel by the plunger.

15 4. A wrapping machine comprising in combination, a wrapping wheel having opposed pockets for receiving articles to be wrapped, connected movable bottoms in said pockets positioned so that when one bottom is pushed 20 into its pocket the depth of an article the other bottom will be substantially flush with the outer surface of the wrapping wheel, means for rotating the wheel so that the openings are alternately presented into receiving and discharging positions, means for introducing an article and a wrapper into a pocket when in receiving position so that the wrapper is gripped between the article and the outermost pocket bottom, a partially 25 wrapped article in the other pocket of the wrapping wheel being ejected by the motion of the connected bottoms caused by the movement of the article into the wheel, and mechanism for moving the connected bottoms to 30 discharge an article from the wheel operative only in the absence of an article to be delivered into the wrapping wheel.

35 5. A wrapping machine comprising, in combination, a wrapping channel, means for delivering wrapping material to intersect the channel, a reciprocable paper guide presenting an open paper-receiving slot into which the paper may drop freely from said means, mechanism for reciprocating the guide across 40 the wrapping channel, and an adjustable paper stop upon which the paper is deposited during the downward motion of the guide.

45 6. A wrapping machine comprising in combination, a wrapping chute having wrapper folding means, a wrapping wheel aligned with the chute and having opposed pockets, means for rotating the wrapping wheel to bring the pockets successively into alignment with the entrance to the wrapping chute, connected movable bottoms in said pockets, a

pusher element movable into and along said chute to feed along it articles delivered thereto from the wrapping wheel, and means to shift said movable bottoms to eject an article from the wrapping wheel, said wrapping wheel and movable bottoms being cut away to permit the entrance of the pusher behind the ejected article.

In testimony whereof I have affixed my signature.

ELMER L. SMITH.

75
